UNITED STATES PATENT OFFICE.

SAMUEL TURNBACH, OF BLOOMSBURG, PENNSYLVANIA.

DESIGN FOR FENCE.

Specification forming part of Design No. **7,448**, dated May 19, 1874; application filed April 4, 1874
[Term of Patent 14 years.]

CASE B.

To all whom it may concern:

Be it known that I, SAMUEL TURNBACH, of Bloomsburg, in the county of Columbia and State of Pennsylvania, have invented a new and original Design for Fence, of which the following is a specification:

The nature of my design is fully represented in the accompanying photographic illustration, to which reference is made.

The design consists of the curved vine-trunk-shaped posts and upright rods with vine-

branches, leaves, and grape-clusters between the trunks, as shown.

I claim as my invention—

The design for a fence, composed of the vine-shaped or sinuous posts and uprights, the latter having branches bearing clusters of grapes, as shown and described.

SAMUEL TURNBACH.
